(57) **CLAIM**

The ornamental design for a bicycle rack, as shown and described.

DESCRIPTION

FIG. 1 is a rear isometric view of the bicycle rack of my design;

FIG. 2 is a left side view thereof;

FIG. 3 is a front elevational view thereof;

FIG. 4 is a top plan view thereof;

FIG. 5 is a left side view thereof;

FIG. 6 is a rear elevational view thereof; and,

FIG. 7 is a bottom plan view thereof.

The broken lines in the drawing depict environmental subject matter and form no part of the claimed design.
